PRESSING IRON

Samuel Dowinsky, New York, N. Y.

Application October 21, 1941, Serial No. 415,883

3 Claims. (Cl. 38—77)

This invention relates to a flat iron designed and adapted for steaming and pressing fabric and other closely analogous materials.

Some of the objects and advantages of the invention are as follows. The iron is capable of generating steam in kind and quantity steadily even though a steaming and pressing operation is carried out constantly over a comparatively long period of time. There is present by virtue of the construction of the iron an improved distribution of the water for generation into steam, while at the same time keeping the pressing surface of the iron from becoming overheated thereby eliminating scorching of the material being ironed. There are provided primary and secondary steam generating means and primary and secondary steam expansion and superheating means wherein steam may be confined and from which it may be released for distribution to the material to be steamed and/or pressed.

In the drawings:

Fig. 1 is a sectional view of a steaming and pressing iron embodying the features of the present invention, the section being taken approximately on the line 1—1 of Fig. 2 and looking in the direction indicated by the arrows;

Fig. 2 is a sectional view taken approximately on the line 2—2 of Fig. 1;

Fig. 3 is a sectional view taken approximately on the line 3—3 of Fig. 1;

Fig. 4 is a sectional view taken on the line 4—4 of Fig. 1;

Fig. 5 is a sectional view taken approximately on the line 5—5 of Fig. 1;

Fig. 6 is a diagrammatic view illustrating the various water and steam generating passages, steam expansion chambers, steam distributing passages and connections between the same, it being understood that some of the connections are exaggerated due to the nature of the illustration.

In accordance with the invention the pressing and steaming iron 10 includes a weighted body 11. The body 11 consists of a base or lower steaming and pressing section 12, an upper steam generating and steam expansion and storing section 13 and a top enclosing section 14. The sections 12, 13 and 14 are held in assembled body forming relation by screw bolts 15 and sections 12 and 13 are further secured to each other by a screw 16. The body 11 is heated by means of an electric heating element 17 of any suitable well-known form, the heating element being held in place between the sections 12 and 13. In the lower section 12 there is a conduit means or pas-

sage 18 consisting of V-shaped branches 19 and 20, respectively, which are interconnected, the branch 19 lying within the branch 20 in the rear portion of the section 12, as shown most clearly in Fig. 3. This conduit means or passage 18 has an inlet 21 in continuation of the branch 19 and an outlet 22 in continuation of the branch 20. The water to be generated into steam is fed to the passage 18 through a coil of tubing 23 which is connected with the inlet 21 by means of a nipple 24. The coil 23 serves as a means for preheating the water. The passage 18 constitutes a primary steam generating means below the heating element 17. This primary steam generating means is connected with a secondary steam generating means in the upper section 13 of the body.

The secondary steam generating means consists of a conduit or passage 25 which extends along the marginal edge portion of the section 13 throughout and ends in a forwardly extending outlet portion 26, shown most clearly in Fig. 4. The outlet 22 of the passage 18 is connected with the inlet 27 of the passage 25 by a tube 28 and suitable couplings 29 and 30, respectively, constituting parts of the connection between the passages 18 and 25 exteriorly of the body 11. The inlet 27 extends upwardly through a boss on the section 13. The passage 25 is in the bottom portion of the section 13 and, therefore, lies directly above the heating element 17.

There are formed in the upper section 13 a first steam chamber 31 and a second steam chamber 32 above the passage 25. The steam chambers 31 and 32 extend substantially throughout the section 13 in the same plane. The chamber 31 extends around the chamber 32 except at the rear thereof. The outlet portion 26 of the passage 25 communicates with the chamber 31 by a port 33 in the bottom wall of the chamber 31. The section 13 has an enlargement 34 formed integral therewith and there is an upflow duct 35 in the enlargement 34 which communicates with the chamber 31 at the rear and at one side of the section 13, and there is also a downflow duct 36 in the enlargement 34 which communicates with the chamber 32, as shown most clearly in Figs. 1 and 6.

In order to control the flow of steam from the chamber 31 to the chamber 32, there is provided a manually operable valve 37 bolted to the enlargement 34 by bolts 38. This valve has ducts 39 and 40 therein which communicate with the ducts 35 and 36, respectively. The ducts 39 and 40 communicate with a passage 41 in the valve

casing. This passage 41 is controlled by a spring-actuated valve member 42 actuated by a hand lever 43 of the valve. By pressing down on the lever 43, steam will flow from the chamber 31 through ducts 35 and 39, passage 40 and ducts 40 and 36 into the chamber 32. When pressure on the lever 43 is released the valve member 42 will be moved automatically to its seat to close the passage 41 and thereby shut off the flow of steam.

The lower section 12 of the body 11 has an A-shaped steam passage 44 therein lying in the plane of the passage 18 and the pointed end extending forwardly, as shown most clearly in Figs. 3 and 6. Portions of the passage 44 have discharge orifices 45 which open through the pressing surface of the base 12. The section 13 has a port 46 therein which establishes communication between the chamber 32 and a duct 47 bored in the screw 16. The duct 47 at the lower end communicates with the cross portion of the passage 44, as appears most clearly in Figs. 1 and 6. It will therefore be understood that when the valve 37 is open steam may flow through the same from the chamber 31 to the chamber 32 and from the chamber 32 through ducts 46 and 47 into the passage 44 and out through the orifices 45. In this manner steam is delivered to the material to be steamed and pressed by the iron manipulated by the handle 48 secured to the bolts 15.

I claim:

1. A flat iron for steaming and pressing including a body consisting of a lower and an up-

per section, the lower section having a pressing surface, primary conduit means in said lower section to receive water for generation into steam, secondary conduit means in the upper section for continuing the generation of steam, 5 a connection between the primary and secondary conduit means, primary and secondary steam expansion chambers in said upper section communicating with said secondary conduit means, 10 heating means to heat said sections, passages in the lower section opening through said pressing surface and communicating with said secondary steam expansion chamber, and means to control the flow of steam from the primary to the secondary steam expansion chamber in order that steam may flow into said passages.

2. In a steaming and pressing iron, a body consisting of a base section and an upper section, heating means arranged between said sections to heat the same, a steam generating passage extending in said base section only at the rear portion thereof and having an inlet and outlet at the rear of the iron, a second steam generating passage extending in said upper section at the marginal edge portion thereof approximately throughout and having an inlet at the rear of the iron, and means establishing communication between the outlet of said first passage and the inlet of the second passage.

3. In a steaming and pressing iron as set forth in claim 2, wherein said first passage consists of interconnected V-shaped branches.
